Patented May 14, 1912.

UNITED STATES PATENT OFFICE.

EDWARD D. SCHMITT, OF BALTIMORE, MARYLAND, ASSIGNOR TO AMERICAN BOTTLE CAP COMPANY, OF BALTIMORE, MARYLAND, A CORPORATION OF DELAWARE.

CAP OR CLOSURE FOR MILK AND OTHER BOTTLES.

1,026,282.

Specification of Letters Patent.

Patented May 14, 1912.

Continuation of application Serial No. 606,666, filed February 4, 1911. This application filed August 21, 1911. Serial No. 645,104.

To all whom it may concern:

Be it known that I, EDWARD D. SCHMITT, a citizen of the United States, residing at Baltimore, State of Maryland, have invented certain new and useful Improvements in Caps or Closures for Milk and other Bottles, of which the following is a specification.

This invention relates to a cap or closure for milk or other bottles.

The ordinary disk closure now commonly used for milk bottles is highly objectionable for several reasons, as their construction permits the closure to be removed and replaced without detection, thus enabling unscrupulous drivers or other persons to remove a portion of the original contents of the bottle and make up the deficiency with water or other adulterant, thus defrauding the ultimate consumer. This disk closure is also unsanitary in that there is a space left between the disk and the upper lip of the jar, which accumulates water, dirt, germs and other objectionable foreign substances, which when the disk is pried out or pulled out, falls into the milk, thus contaminating it and rendering it unfit for use. Further, the jar now in use, in order to accommodate the disk, has an annular groove in the inner wall just below the lip. This accumulates milk which sours and becomes objectionable and the formation of the jar is such that it is washed or cleaned with difficulty.

My object is to overcome all of these objections, which I do by providing a cap of easily rupturable material, which is adapted to be crimped or indented into locking contact with the shoulder on the outside of the mouth of the bottle. This cap is so formed that any attempt to remove the same may be readily detected and it is so constructed that when a portion of the cap has been torn out a sufficient portion to enable the cap to be removed, the cap will still retain sufficient rigidity to be sprung back upon the neck of the bottle and held there by the locking indentations with sufficient force to stopper the bottle temporarily. These and other objects and advantages will become apparent in the course of the following description.

In the drawings—Figure 1 is a perspective view of the cap applied; Fig. 2 is a similar view showing the cap with the tear-

able portion being torn therefrom; Fig. 3 is a similar view showing the manner in which the cap may be readily removed after the tab portion has been torn out, leaving the cap in condition to be re-applied, for temporarily stoppering; Fig. 4 is a sectional view with the cap applied, showing the disk employed in the top of the cap; Figs. 5 and 6 are modifications, showing a different way of marking or lining the metal in the cap, to guide the tearable portion in the unsealing operation.

Referring to the drawings, and particularly to Figs. 1, 2 and 3, wherein the preferred embodiment of the invention is shown, the numeral 1 designates the upper portion of a bottle neck, formed with a rounding lip 2 and a locking shoulder 3.

The numeral 4 designates the cap, which, as before suggested, is preferably made of the lightest tin obtainable, which I have found in practice to be sufficiently rigid to enable it to be tightly or firmly locked to the bottle, and at the same time, sufficiently weak to be easily tearable or rupturable. It is formed preferably with a flat upper surface 5 against which normally rests a disk of card board, straw-board or other suitable material 6, which may be treated with paraffin or other suitable material to make it impervious to liquid and at the same time, render it more sanitary.

The numeral 7 designates a flange adapted to be indented at intervals as indicated at 8 into locking engagement with the locking shoulder 3 of the bottle. At one side of the flange, I provide two vertical indentations 9, which terminate at their lower ends in short slits 10 on each side of a tab 11. The vertical indentations run into linear converging indentations 12, which extend to a point near the center of the cap, as shown.

The vertical indentations 9 and slits 10 serve as starting means for tearing the cap and the converging linear indentations 12, which in this form are made by indenting the metal along straight lines, from the inside out, serve as guiding lines upon which the material will be torn and they are so arranged that the cap is invariably torn to a definite point. This insures, at all times in opening the cap, the accurate tearing of the same, since the converging lines or mark-

ings are those upon which the metal would naturally tear if the indentations were not present. However, I have found in practice that if the indentations or guiding markings are made to converge, the tab portion will invariably tear to the end, which is highly advantageous, since it is my purpose to tear the cap invariably the same distance, so as to leave, with absolute certainty, enough material in the cap to give it a springy action in replacing the same, after the original seal has been broken.

Adjacent to the tab and on each side thereof, I provide depending lugs 13 preferably integral with the flange. These lugs are turned up or folded upon themselves at their lower ends, to form comfortable finger pieces 14, by which the cap may be readily forced from the top of the bottle by the two thumbs of the operator, without the necessity of touching any other part of the cap.

In the modifications shown in Figs. 5 and 6, the guiding lines are constituted by two converging rows of perforations 15 which, in Fig. 5 are shown as slightly elongated nicks and in Fig. 6 round perforations. Otherwise, the construction is like that shown in the preferred form.

The cap is adapted to be applied by machinery in the bottling establishment, by indenting the flange at intervals as shown, but it will be understood that the flange of the cap may be forced into locking engagement with the locking shoulder in any suitable manner, as for instance, by spinning. It will be noted that the lugs 13 are below the flange and that a portion of the tab 11 virtually forms a continuation of the flange, so that in the locking operation, the locking devices will operate upon the tab as well as those portions of the flange immediately above the lugs, thus producing, for all practical purposes, a continuous flange.

To remove the cap, it is only necessary to grasp the tab 11 and exert an upward force upon the same, when it will tear along the converging markings. When the tab and its integral material is torn to the desired point, at the end of the markings, the cap will be left with a substantially V-shape opening at the top, but the contents of the bottle will not be exposed, because of the presence of the disk 6. However, the removal of the material which the tab has taken with it, will break the lock of the seal and a slight upward pressure applied to the lugs, will spring the cap sufficiently to remove it. After a part of the contents has been removed, the cap with its contained disk may be sprung in place on the bottle, as a temporary closure and ultimately thrown away, when the entire contents of the bottle has been used.

From the foregoing description, it will be seen that I have produced a cap which

admirably meets with the requirements in handling milk, from both mechanical and sanitary standpoints, and one which, while it can be readily ruptured to destroy the original seal and make interference or tampering with the seal perfectly obvious, will at the same time, leave the cap sufficiently strong to be replaced upon the bottle, for the purpose of keeping the bottle substantially air-tight, and preventing waste of the contents.

In stoppering milk bottles where a food product is involved which is one of the best known foods for germ culture, the advantages of a closure such as has been described, will at once be obvious, but while the seal is especially adapted for milk bottles, it may be put to other uses, where a cap of this general character will be practical.

This application is a continuation of my application Number 606,666, filed February 4, 1911, and abandoned in favor of the present application.

Having thus described my said invention, what I claim is:—

1. A bottle cap of easily rupturable material, formed with a flange adapted to make locking contact with a locking surface on the exterior of a bottle neck, said flange being provided with markings to serve as starting means for tearing the cap, converging linear markings in the top of the cap, said top markings ceasing at a point approximate to the center of the cap, the top markings being a continuation of the markings of the flange, the part within said markings being adapted to be torn out along said markings, whereby the seal is broken without rendering the cap unfit as a temporary seal.

2. A bottle cap of easily rupturable material, formed with a flange adapted to make locking contact with a locking surface on the exterior of a bottle neck, said flange being provided with linear indentations to serve as starting means for tearing the cap, converging linear indentations in the top of the cap, forming a continuation of the indentations in the flange, the top indentations intersecting at a point approximate to the center of the cap, whereby the tearable portion of the cap is made to invariably follow the lines of indentations, and a tab integral with the flange portion of the cap between the flange indentations.

3. A bottle cap of easily rupturable material, formed with a flange adapted to make locking contact with the exterior of a bottle neck, said flange being provided with linear indentations, linear indentations in the top of the cap and running into the indentations in the flange, the flange indentations serving as starting means for tearing the cap, and the top indentations as guiding lines upon

which the cap is torn, a lug at each side of the flange indentations, serving as means for readily removing the cap, after the seal has been broken, substantially as and for the 5 purpose set forth.

4. A bottle cap of easily rupturable material formed with a flange adapted to make locking contact with a locking surface on the exterior of a bottle neck, said flange being 10 provided with indentations to serve as starting means for tearing the cap, converging linear indentations in the top of the cap running into the flange indentations, a tab integral with the flange and adapted to 15 serve as means for readily tearing the cap, and a lug on the flange on each side of the tab, substantially as and for the purpose set forth.

5. A bottle cap of easily rupturable material, formed with a flange adapted to make locking contact with a locking surface on the exterior of a bottle neck, said flange being slotted at two points for about one-half its depth, indentations in the flange 25 running into said slits, linear indentations in the top of the cap, intersecting at a point approximate to the center of the cap, and serving as guide lines for tearing the cap, a tab integral with the flange between the 30 slits and lugs on each side of the tab, substantially as and for the purpose set forth.

6. In a closure for bottles or jars, the combination of a jar having an annular locking surface on the exterior of its neck, a cap of 35 easily rupturable material formed with a flange adapted to make locking contact with said locking surface, said flange being pro-

vided with markings to serve as starting means for tearing the cap, converging markings in the top of the cap, the said top markings ceasing at a point approximate to the center of the cap, the top markings being a continuation of the markings of the flange, the part within said markings being adapted to be torn out along the lines of the 40 markings, whereby the seal is broken, without rendering the cap unfit as a temporary seal and a disk of suitable material between the cap and the bottle lip and held in place by the cap.

7. As an article of manufacture, a bottle cap of easily rupturable material formed with a flange adapted to make locking contact with a locking surface on the exterior of a bottle neck, said flange being provided with markings to serve as starting means for tearing the cap, converging linear markings in the top of the cap, said top markings ceasing at a point short of the entire width of the cap, the top markings being a continuation of the markings of the flange, the part within said markings being adapted to be torn out along said markings, whereby the seal is broken without rendering the cap unfit as a temporary seal, and a disk contained in the cap 55 for the purpose of covering the opening in the cap when the same has been torn.

In testimony whereof I affix my signature in presence of two witnesses.

EDWARD D. SCHMITT.
